UNITED STATES PATENT OFFICE.

EZRA B. LAKE AND JESSE S. LAKE, OF ABSECOM, NEW JERSEY.

IMPROVEMENT IN CIRCUIT-CLOSERS FOR TELEGRAPHS.

Specification forming part of Letters Patent No. **35,694**, dated June 24, 1862.

To all whom it may concern:

Be it known that we, EZRA B. LAKE and JESSE S. LAKE, of Absecom, in the county of Atlantic, in the State of New Jersey, have invented a new and Improved Self-Acting Circuit-Closer for Telegraph-Keys; and we do hereby declare that the following is a full, clear, and exact description of the construction and operation of the same, reference being had to the annexed drawings, making a part of this specification, in which—

Figure 1 is a side view. Fig. 2 is another side view of one end of a telegraph-key, showing the circuit-closer up. Fig. 3 is a top view.

Like letters refer to like parts in all figures.

B is a metallic saddle with standards B' B'. What we mean by saddle and its standards is that part of the telegraph-keys now in common use to which one of the wires comes in contact while the other is attached to it by some suitable non-conductor, and it may be made in any known suitable form. It may also be connected to the telegraph-wire in any of the known suitable forms. C is a metallic key working in the standards B' B'. It has an adjuster, L, which is so adjusted that when the adjuster L is pressed on the saddle-plate B, the said key C is clear of the anvil F, and if the circuit-closer D is up, as shown in Fig. 2, the circuit will be broken. The metallic anvil F is attached to the saddle B in any suitable known form. The said an-

vil F has a lip or rim around it near its upper end, on which the metallic circuit-closer D rests when it closes the circuit. The circuit-closer D is hinged to the key C at P, and works loosely in the slot N of the key C.

E is a thumb-piece fast to the upper edge of the circuit-closer D. The shape of the said circuit-closer D is shown by full and dotted lines; but we do not confine ourselves to this shape alone.

When the operator wishes to send a message over the wires, he will press the thumb-piece down on the end of the key C, which causes the circuit-closer D to stand in the position shown by Fig. 2. When the operator leaves the instrument the circuit-closer D, by its own weight, or by the help of a spring, falls back on the lip of the anvil F, thus forming a self-closing circuit, thus avoiding the evil consequence arising from the neglect to close the circuit, which is often the case with the operator under the old form.

What we claim as new, and desire to secure by Letters Patent, is—

The circuit-closer D, combined with the telegraph key C, substantially as herein set forth.

EZRA B. LAKE.
JESSE S. LAKE.
